(57) **CLAIM**

The ornamental design for a spray hood, as shown and described.

DESCRIPTION

FIG. 1 is an upper perspective view of a spray hood;
 FIG. 2 is a front elevation view of the spray hood of FIG. 1;
 FIG. 3 is a rear elevation view of the spray hood of FIG. 1;
 FIG. 4 is a left side elevation view of the spray hood of FIG. 1;
 FIG. 5 is a right side elevation view of the spray hood of FIG. 1;
 FIG. 6 is a top plan view of the spray hood of FIG. 1; and,
 FIG. 7 is a bottom plan view of the spray hood of FIG. 1.
 The broken lines immediately adjacent areas of the design represent the bounds of the claimed design while other broken lines are directed to environment and are for illustrative purposes only; features illustrated in broken lines form no part of the claimed design.
